COMBINATION EYEGGLASS HOLDER AND TRAY

Edward F. Olsen, Hillman, Mich.

Application March 23, 1959, Serial No. 55,141

Term of patent 14 years

(Cl. D57—1)

Fig. 1 is a perspective view of a combination eyeglass holder and tray showing my new design.

Fig. 2 is a side elevational view thereof.

Fig. 3 is a rear elevational view thereof.

Fig. 4 is a vertical sectional view taken through the center thereof.

The side not shown is exactly the same in appearance as shown in Fig. 2.

I claim:

The ornamental design for a combination eyeglass holder and tray, as shown and described.
